(57) **CLAIM**

The ornamental design for an adaptable bracelet device, as shown and described.

DESCRIPTION

FIG. 1 is a perspective view of an adaptable bracelet device according to the present application.

FIG. 2 is a front view of the adaptable bracelet device of FIG. 1.

FIG. 3 is a back view of the adaptable bracelet device of FIG. 1.

FIG. 4 is a right view of the adaptable bracelet device of FIG. 1.

FIG. 5 is a left view of the adaptable bracelet device of FIG. 1.

FIG. 6 is a top view of the adaptable bracelet device of FIG. 1.

FIG. 7 is a bottom view of the adaptable bracelet device of FIG. 1.

FIG. 8 is an exploded view of the adaptable bracelet device of FIG. 2.

FIG. 9 is an alternate perspective view of the adaptable bracelet device of FIG. 2.

FIG. 10 is a perspective view of an embodiment of the adaptable bracelet device of FIG. 1; and,

FIG. 11 is an alternate perspective view of the adaptable bracelet device of FIG. 10.

The broken lines are included for the purpose of illustrating environmental structure and form no part of the claimed design.

1 Claim, 7 Drawing Sheets
